(57) **CLAIM**

The ornamental design for a box and ribbon set, as shown and described.

DESCRIPTION

FIG. 1 is a top view of a first embodiment of the box and ribbon set showing the design;

FIG. 2 is a bottom view thereof;

FIG. 3 is a perspective view thereof shown in a folded position and with an environmental bow shown in broken lines;

FIG. 4 is a top plan view thereof;

FIG. 5 is a front side elevation view thereof;

FIG. 6 is a left side elevation view thereof;

FIG. 7 is a right side elevation view thereof;

FIG. 8 is a back side elevation view thereof;

FIG. 9 is a bottom view thereof;

FIG. 10 is an environmental perspective view thereof shown in a presentation position;

FIG. 11 is a top view of a second embodiment of the box and ribbon set showing the design;

FIG. 12 is a bottom view thereof;

FIG. 13 is an environmental perspective view thereof shown in a presentation position;

FIG. 14 is a top view of a third embodiment of the box and ribbon set showing the design;

FIG. 15 is a bottom view thereof;

FIG. 16 is a perspective view thereof shown in a folded position and with an environmental bow shown in broken lines;

FIG. 17 is a top plan view thereof;

FIG. 18 is a front side elevation view thereof;

FIG. 19 is a left side elevation view thereof;

FIG. 20 is a right side elevation view thereof;

FIG. 21 is a back side elevation view thereof;

FIG. 22 is a bottom view thereof; and,

FIG. 23 is an environmental perspective view thereof shown in a presentation position.

The top, front, left side, right side, back side, and bottom views of the second embodiment in the folded position and

(Continued)

with the unclaimed bow are identical to FIGS. 4 to 9. The double jagged lines across the sides of the box or width of the ribbon represent an indefinite length. The double jagged lines along the length of the ribbons represent an indefinite width. The appearance of any portion of the article between the break line forms no part of the claimed design. The ribbon is flexible. The diagonal shading shown in FIGS. 11 and 13 represents a reflective sheen. The grayscale shading shown in FIGS. 14 to 23 represents contrasting tones. The broken lines shown represent portions of the box and ribbon set and environmental subject matter, all of which form no part of the claimed design.
